UNITED STATES PATENT OFFICE.

JOHN J. RIGBY, OF NEW YORK, N. Y., ASSIGNOR TO E. W. BLISS COMPANY, A CORPORATION OF WEST VIRGINIA.

NECKING-MACHINE.

No. 800,764.

Specification of Letters Patent.

Patented Oct. 3, 1905.

Application filed January 18, 1904. Serial No. 189,392.

To all whom it may concern:

Be it known that I, JOHN J. RIGBY, a citizen of the United States of America, and a resident of the city of New York, borough 5 of Brooklyn, county of Kings, and State of New York, have invented certain new and useful Improvements in Necking-Machines, of which the following is a specification.

My invention relates generally to a machine 10 for expanding or deflecting a portion of a shell or blank, and has reference, so far as the structure shown in the present application is concerned, to a necking-machine.

The object had in view is the production of 15 a simple and effective structure capable of performing the work noted above.

The present form of my invention is particularly adapted to expand the body portion 20 of a shell of sheet material, the said shell having previously been drawn up or otherwise formed to a size corresponding with the size of neck desired.

In carrying out my invention I employ a stationary work-holding device, a rotatable 25 chuck carrying a plurality of expander-rollers, an expander for the rollers of the chuck, and in the present instance a plurality of clasping-jaws for holding the blank or shell on the work-holding device.

Other improvements will appear as the specification proceeds.

In the accompanying drawings I have shown my invention embodied in a suitable form; but changes may of course be made and elements omitted without departing from the invention.

In the said drawings, Figure 1 is a vertical sectional view on the line 1 1 of Fig. 2 of a machine embodying my invention. Fig. 2 is 40 a front elevation. Figs. 3 and 4 are vertical sectional views of the work-holding device, rotatable chuck, &c., showing the elements in two different positions. Fig. 5 shows the development of the blank or shell.

Similar characters of reference indicate corresponding parts in the different views.

1 denotes a framework of any suitable construction for properly supporting the parts of the machine.

2 indicates the stationary work-holding device, provided with a circumferential flange 3, on which the shell or blank is placed.

4 is a rotatable chuck located inside of the stationary work-holding device and carrying

a plurality of expander-rollers 5, in the present 55 instance two, mounted on wedge-shaped portions 6, located in the slot 7 of the said chuck. Interposed between the wedge-shaped portions in the slot 7 is a tapered expander 8, mounted on the shaft 9, which in this case is 60 continuously revolving, thereby causing the chuck 4 to rotate with it. Springs 10 normally hold the wedge-shaped members in their contracted position. As will be seen from an inspection of Fig. 1, the expander-rollers 65 5 project to a point beyond the circumferential flange 3 of the stationary work-holding device.

Located in front of the machine and on either side of the stationary work-holding device and 70 of the expander-rollers are two jaws 11, sliding in the guides 12 and adapted to close in over the blank mounted on the stationary work-holding device. These jaws are constructed or formed with a surface 13 of substantially 75 the same diameter as the outside diameter of the circumferential flange 3—that is, substantially equal to the diameter of the neck portion of the shell or blank. This surface 13 is coextensive with the circumferential flange 80 3. Next to this surface 13 is another surface 14 of a larger diameter—that is, of a diameter equal to the diameter of the body portion to be formed on the blank or shell. This surface 14 is coextensive with the expander-rollers. Beyond this surface 14 is located a surface 15, which extends in over the end of the shell or blank and of a diameter smaller than the diameter of the body portion of the blank to be formed, so as to prevent lateral displacement.

Sliding in the framework and in the vertical guide 16 of the same is a sliding member 17, connected to the treadle 18 by means of the rod 19 and plate 20. The plate 20 is connected to the sliding jaws by means of the toggle-links 21. The spring 22 normally holds the treadle 18 in its uppermost position, and consequently the slider 17 up against that portion of the framework which is denominated 95 by 23. A cushion 24, of rubber or other soft material, is provided on the slider 17, so as to prevent any undue jar when the parts return to their normal position. Moving with the slider is a member 25, sliding in the guides 100 26 on the rear side of the framework. The shaft 9 is rotated continuously by means of a pulley 27 or by other suitable means and is

provided with a collar 28, mounted fast on the same.

29 is a bell-crank mounted at 30 and connected with a sleeve 31, sliding on the shaft 5 9. The bell-crank 29 is attached to the slider 17 by means of the links 32 and 33. Link 33 is provided with an adjustable screw 34, which acts as a stop against the bed-plate 35.

The whole machine is in this case of a very small size and is conveniently mounted on a working bench and connected to the treadle 18 on the floor.

The blank to be acted upon is struck up in the present instance into a shell having a diameter equal to the diameter of the size of neck desired on the said shell or blank. This shell is then placed upon the work-holding device. The treadle 18 being depressed, the two jaws 11 close in over the same, the surface 13 binding the neck portion to the circumferential flange 3 and the surface 15 extending in over the blank, so as to prevent lateral displacement of the same. The parts are so arranged that the toggles 21 are adapted to straighten out and to be moved approximately on the dead-center to close these jaws 11 in over the blank in the manner just set forth, while the sleeve 31 moves the distance from the position shown in Fig. 1 up to the fast collar 28. The depression of the treadle being continued, the sleeve 31 being in contact with the collar 28 will carry the shaft 9 with it, thereby causing the expander 8 to move the two wedge-shaped portions 6 into their expanded position, whereby the expander-rollers also are moved into their expanded position. The shaft 9 revolving continuously will cause the expander-rollers to expand the body portion of the shell until it reaches the surface 14 of the jaws 11, while the size of the neck portion remains the same. This extra movement to enable the expander to move the wedge-shaped portions into their expanded positions will not affect the position of the jaws 11 materially, inasmuch as the toggle-links 21, operating the same, are approximately on the dead-center, and the movement needed to move the said expander-rollers into their expanded position being comparatively slight its effect will not be felt by the jaws 11, as whatever movement there might be would be taken up by the said toggles 21. When the treadle 18 is released, the spring 22 moves it up again automatically, and the slider 17, together with the members moving in unison with the same, returns it to its uppermost position, the cushion 24 preventing any undue jar of the machine. Simultaneously with this the expander 8 is withdrawn, the spring 10 forcing the wedge-shaped portions down into their contracted position. The return movement of the treadle retracting the expander 8 and moving the jaws 11 away from the work will permit the finished blank to be removed. The development of the blank is indicated in Fig. 5.

What I claim is ...

1. In a machine of the character set forth, the combination with a stationary work-holding device, a circumferential flange on the same for receiving the blank, a rotatable 70 chuck, a plurality of expander-rollers carried by the said chuck extending beyond the circumferential flange of the work-holding device, means for moving said rollers into their expanded position, a plurality of jaws adapted to 75 clasp the blank, a surface 13 on said jaws, adapted to come in contact with the blank, of a diameter substantially equal to the diameter of the blank when the jaws are closed, co-extensive with the circumferential flange, another surface 14 on said jaws of a diameter somewhat greater than that of the surface 13 and equal, when the jaws are closed, to the diameter of the size of the blank when expanded, and coextensive with the expander-rolls, a third surface 15 on said jaws of a smaller diameter and adapted to prevent the blank from lateral displacement on the work-holding device when the jaws are closed. 85

2. In a machine of the character set forth, 90 the combination with a stationary work-holding device, a circumferential flange on the same for receiving the blank, a rotatable chuck, a plurality of expander-rollers carried by the said chuck extending beyond the circumferential flange of the work-holding device, a plurality of jaws adapted to clasp the blank, a surface 13 on said jaws adapted to come in contact with the blank, of a diameter substantially equal to the diameter of the 100 blank when the jaws are closed, coextensive with the circumferential flange, another surface 14 on said jaws of a diameter somewhat greater than that of the surface 13 and equal when the jaws are closed, to the diameter of 105 the size of the blank when expanded, and coextensive with the expander-rolls, a third surface 15 on said jaws of a smaller diameter and adapted to prevent the blank from lateral displacement on the work-holding device when the jaws are closed and means for closing the 110 jaws first and then moving the expander-rollers into their expanded position.

3. In a machine of the character set forth, the combination with a stationary work-holding device, a circumferential flange on the same for receiving the blank, a rotatable chuck, a plurality of expander-rollers carried by the said chuck extending beyond the circumferential flange of the work-holding device, a plurality of jaws adapted to clasp the blank, a surface 13 on said jaws adapted to come in contact with the blank, of a diameter substantially equal to the diameter of the blank when the jaws are closed, coextensive with the circumferential flange, another surface 14 on said jaws of a diameter somewhat greater than that of the surface 13 and equal when the jaws are closed, to the diameter of the size of the blank when expanded, and co- 130

extensive with the expander-rolls, a third surface 15 on said jaws of a smaller diameter and adapted to prevent the blank from lateral displacement on the work-holding device 5 when the jaws are closed, and means for closing the jaws first and then moving the expander-rollers into their expanded position by an uninterrupted movement.

4. In a machine of the character set forth, 10 the combination with a stationary work-holding device, of a rotatable chuck, a plurality of expander-rolls in said chuck, a plurality of clasping-jaws, a rotatable shaft, an expander for the expander-rolls carried by the said shaft 15 and adapted to impart the motion of the shaft to the chuck, means for moving the jaws into their closed position and then causing the expander to move the expander-rollers into their expanded position.
5. In a machine of the character set forth, 20 the combination with a stationary work-hold-

ing device, of a rotatable chuck, a plurality of expander-rolls in said chuck, a plurality of clasping-jaws, a rotatable shaft, an expander for the expander-rolls carried by the said shaft 25 and adapted to impart the motion of the shaft to the chuck, a collar fast on the shaft, a sleeve loose on the shaft, means for moving the jaws into their closed position and simultaneously therewith sliding the sleeve up to 30 the fast collar, the continued motion causing the sleeve to engage the collar to move the shaft laterally so as to cause the expander to move the expander-rollers into their expanded position. 35

Signed at Brooklyn, New York, this 16th day of January, 1904.
